UNITED STATES PATENT OFFICE.

LEWIS W. TURNER, OF WALLINGFORD, CONNECTICUT, ASSIGNOR TO GEORGE W. HAUXHURST, OF PATERSON, NEW JERSEY.

CURRY-COMB.

SPECIFICATION forming part of Letters Patent No. 358,510, dated March 1, 1887.

Application filed November 18, 1886. Serial No. 219,247. (No model.)

To all whom it may concern:

Be it known that I, LEWIS W. TURNER, a citizen of the United States, residing at Wallingford, in the county of New Haven, State of Connecticut, have invented certain new and useful Improvements in Curry-Combs, of which the following is a specification, reference being had therein to the accompanying drawings.

10 The object of my invention is to produce a simple, cheap, and durable curry-comb.

Curry-combs have in some instances been provided with teeth made of wire bent in various ways. My invention therefore consists 15 in the improved form of teeth hereinafter described and claimed.

In the accompanying drawings, illustrating 20 my invention, Figure 1 is a view of one side of the comb. Fig. 2 is an edge view; and Fig. 3, a sectional view taken on a plane at right angles to the plane of the body of the comb and on the line $x-x$, Fig. 1.

Where like letters of reference occur in the different figures they designate corresponding 25 parts.

The letter A designates the comb-frame, which is composed of the handle a and body portion b , made of wood or other suitable material and in one piece.

30 The letters B designate the pieces of wire forming the teeth.

Each piece of wire is bent or formed so that its end portions, c , lie parallel to each other and its middle portion extends inward in the 35 form of a loop between the parallel portions a distance somewhat less than their whole length, whereby two bends or loops, d , are formed. Each piece of wire when so bent makes four teeth, the two bends or loops d serving as blunt teeth on one side of the comb, while the ends of the parallel portions c serve as sharp teeth on the opposite side.

The teeth are secured in the comb-frame by driving the ends of the parallel portions c 40 through the same, so that said portions will project at the opposite side and the end of the

bend or loop that extends inward between the parallel portions is in contact with the surface of the body portion b . A supplementary staple or fastening device, e , driven into the body over 50 the end of the inwardly-extending loop, may be employed, if desired.

A comb constructed as hereinbefore described is adapted for use on animals having skins which differ in thickness and sensitivity. The pieces which form the teeth are arranged in rows, as shown, or in any other manner desired.

It is plain that any number of loops or bends extending inward between the parallel portions of the wire may be made.

What I claim as my invention, and desire to secure by Letters Patent, is—

1. A curry-comb consisting of the frame having a body portion, b , and handle a , said body portion being provided with teeth made of pieces of wire, each of which is bent at its middle portion to form parallel sides c , bends d , and an inwardly-extending loop, said pieces being secured to the body portion, with the 60 ends c projecting at one side of the body portion and the bends d projecting at the other side, whereby sharp teeth and blunt teeth are provided on opposite sides, as set forth:

2. A curry-comb consisting of the frame 75 having a body portion, b , and handle a , said body portion being provided with teeth made of pieces of wire, each of which is bent to form parallel sides c , bends d , and an inwardly-extending loop, said pieces being attached to 80 the body portion with the ends of the parallel portions projecting at one side and the bends or loops at the other, and staples e driven into the body portion over the inwardly-extending loop, as set forth.

In testimony whereof I affix my signature in presence of two witnesses.

LEWIS W. TURNER.
